Primary Examiner — Cathron C Brooks*Assistant Examiner* — Sharon S Oum(74) *Attorney, Agent, or Firm* — Middleton Reutlinger(57) **CLAIM**

The ornamental design for a fan, as shown and described.

DESCRIPTION

FIG. 1 is an upper perspective view of a fan design;
FIG. 2 is a top view of the fan design of FIG. 1;
FIG. 3 is a bottom view of the fan design of FIG. 1;
FIG. 4 is a first side view of the fan design of FIG. 1;
FIG. 5 is a second side view of the fan design of FIG. 1;
FIG. 6 is a front view of the fan design of FIG. 1;
FIG. 7 is a rear view of the fan of FIG. 1; and,
FIG. 8 is a lower perspective view of the fan of FIG. 1.
The broken line disclosure represents unclaimed portions of the fan in which the design is embodied.
